INK PAD FOR STENCIL DUPLICATORS

Ralph L. Johnson, Brockton, Mass.

Application July 31, 1944, Serial No. 547,475

3 Claims. (Cl. 101—125)

(Granted under the act of March 3, 1883, as
amended April 30, 1928; 370 O. G. 757)

1

The invention described herein, if patented may be manufactured and used by or for the Government for governmental purposes, without the payment to me of any royalty thereon.

The present invention relates to a stencil printer for reproducing typewritten and drawn matter from stencil sheets and has for its primary object to provide an inexpensive construction of printer for use in a more or less minor capacity where only small runs are required, or where a standard duplicating machine is not available.

To this end it is a further object of the invention to provide a stencil printer which is not only composed of readily available material but also one which is composed of relatively inexpensive materials which may be easily and quickly assembled into the completed articles.

Another object of the invention resides in the use of relatively narrow strips of impervious or ink-repellent material applied to certain of the edges of the duplicating device to prevent the ink from spreading, and thereby avoiding contamination of the stencil and related parts.

A further object of the invention consists in the use of removable strips of duplicating paper applied over the strips of ink-repellent material and overlapping to some extent the operative surface of the duplicator to further lessen the possibility of contamination of the stencil, etc.

Other objects and advantages of the invention will be apparent from the following description when taken in connection with the accompanying drawings, in which,

Figure 1 is a perspective view of the novel duplicating device, showing a portion of a conventional stencil sheet in position thereon.

Figure 2 is a longitudinal sectional view taken on line 2—2 of Figure 1, on an enlarged scale.

Figure 3 is a transverse sectional view taken on line 3—3 of Figure 1, and

Figure 4 is a plan view of the printer with parts broken away.

Referring to the drawings in greater detail and particularly to Figures 2 and 3, the numeral 1 indicates a wood base or backing member for the printer, which, in accordance with the present invention, is formed of plywood so as to eliminate warping. Mounted upon the upper face of the backing 1 and coextensive therewith except for a space of about 2½ inches at the head of the base member, is a cushion 2. This cushion is formed of paper laminations, preferably newspaper, and should have a thickness of about ½ of an inch to provide the most favorable cushioning effect. An ordinary stapling machine, used as a tacker, may

2

be conveniently employed for inserting staples 3 to permanently secure the cushion pad to the backing member 1.

The numeral 4 indicates a sheet of ink-repellent material such as "oil-board," which is an oil-impregnated paper often used in stenciling crates and the like, and which provides an excellent shield for the cushion 2. This impervious sheet extends throughout the length and width of the base member 1 and may have its ends passed around the ends of the base 1 and secured to the under-side thereof as shown in Figures 1 and 2. Screws 5, spaced transversely of the base member in accordance with the spacing of the apertures 15 of the conventional stencil sheet, also serve to secure the oil-board to the backing member at its upper end, and the side edges of this covering sheet may be secured to the backing by series of staples or the like. It will be understood of course that the heads of the screws 5 are spaced above the impervious sheet 4 so as to provide an anchoring means for the conventional stencil sheets to be used with the printer.

Mounted on the sheet 4 and coextensive with the cushion 2 is a sheet of absorbent material 6 used as a reservoir for a moderate supply of ink and as a dispenser thereof through the stencil to the sheet being printed. This sheet is likewise tacked to the base member 1 by a stapling machine or the like, and it is desirable to employ double rows of closely-spaced staples for this purpose so as to firmly and securely anchor the sheet. The material used for the ink-retaining sheet 6 is preferably flannel as it shrinks slightly when moistened, thereby providing a taut, smooth surface and eliminating any possibility of wrinkles which would greatly interfere with the accurate reproduction, of the designs or the like formed on the stencil.

It will be understood of course that in use, the flannel sheet 6 is saturated with ink, and in order to avoid excessive spreading of the ink beyond the operative surface of the printer, relatively narrow strips 7 of ink-repellent material, such as oil-board, are arranged to overlie and engage the longitudinal margins and lower margin of the ink-retaining sheet. These strips are secured in position by series of staples or the like 8 which are located adjacent the inner edges of the strips 7 so as to insure close contact between the strips and flannel sheet along the three edges referred to. Wood strips 9 are preferably mounted upon the strips 7 at the three edges thereof to further secure the latter in place and to provide a suitable finish for the device.

A supplemental means which may be used to avoid excessive spreading of the ink consists of strips 10 of duplicating paper. Such strips are placed over the oil-board strips and extend from the inner edges of the wood strips 9 to a point slightly under the stencil sheet when placed in position on the printer. These paper strips are usually serviceable for one series of operations, after which they have generally become sufficiently ink-saturated to require replacement. In ordinary operation it is desirable to employ new strips 10 at the initiation of each series of operations.

The purpose and function of each of the several elements of the printer have been fully described in connection with the detailed description of its construction and need not be repeated. Suffice it to say that after the flannel sheet 6 is saturated with ink, the stencil 11 is inverted and the openings in its heading are passed over the screws 5. The sheet to be printed is then applied to the stencil and rolled once with a photographic print roller or the like. In this operation the roller is placed at the end of the paper adjacent the screws 5, where the stencil is anchored, and moved toward the opposite end thereof, and it is desirable to raise the paper immediately behind the roller so as to avoid excessively heavy reproductions. After the particular series of reproductions has been completed, it is usual to remove the strips 10, which have become saturated with ink, as heretofore indicated, and apply new strips 10 when the device is to be again placed in operation.

From the foregoing description taken in connection with the accompanying drawings it will be apparent to those skilled in the art that I have devised an exceedingly simple and inexpensive stencil printer formed of relatively few parts, and yet one which is provided in a simple manner with sufficient safeguards to insure high-quality reproductions.

In accordance with the patent statutes I have described what I now believe to be the preferred form of the invention, but inasmuch as various minor changes may be made in the details of construction without departing from the spirit of the invention it is intended that all such changes be included within the scope of the appended claims.

What is claimed is:

1. A stencil printer including a base member, a cushion member mounted thereon, a sheet of oil-board or similar impervious material cover-

ing the cushion member, a sheet of absorbent material disposed upon the sheet of impervious material, relatively narrow strips of impervious material mounted on the face of the absorbent material at certain of the edges thereof, rows of closely spaced staples for fastening together said base member, cushion member, oil-board covering, absorbent material and narrow strips, and wood strips for further clamping said strips of impervious material on the edges of the absorbent sheet.

2. A stencil printer including a base member of plywood, a cushion member comprised of a pad of newspapers mounted on the base member, a sheet of oil-board covering the cushion member, a sheet of absorbent material disposed upon the sheet of oilboard, relatively narrow strips of impervious material mounted on the face of the absorbent material at certain of the edges thereof, and rows of closely spaced staples for fastening together said base member, cushion member, oil-board covering, absorbent material and narrow strips.

3. A stencil including a base member, a cushion member mounted thereon but spaced from one end thereof, a sheet of impervious material covering the cushion member and the exposed portion of the base member, a plurality of fastening means for securing an end of the impervious sheet to the exposed portion of the base member, said fastening means being spaced a substantial distance from the adjacent edge of the cushion member, and being spaced transversely of the base member in accordance with the spacing of the openings in conventional stencil sheets, a sheet of absorbent material co-extensive with the cushion member and mounted on the impervious sheet, and relatively narrow strips of impervious material mounted on the face of the absorbent sheet at certain of the edges thereof.

RALPH L. JOHNSON.
